UNITED STATES PATENT OFFICE

RALPH E. HYDE, OF CLEVELAND, OHIO, ASSIGNEE TO THE OSTER MANUFACTURING COMPANY, OF CLEVELAND, OHIO, A CORPORATION OF OHIO

STAMPED DIESTOCK

Application filed February 18, 1928. Serial No. 255,286.

The present invention relates, as indicated, to a stamped die stock, and the primary object thereof is to form a die stock of the two-block type from pressed steel. To the accomplishment of the foregoing and related ends, said invention then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

15 In said annexed drawing:

Fig. 1 is a plan view of a die stock of the character described; Fig. 2 is an end elevation thereof; and Fig. 3 is a longitudinal section therethrough.

20 Referring more particularly to the drawings, the die stock comprises a lower member 1 and an upper member 2, said members being suitably secured together. Member 1 is provided with a tubular projection 3 adjacent its midpoint, and with a pair of nubs 4 equidistantly spaced from said projection on opposite sides thereof. Beyond said nubs, said member 1 is provided adjacent each end with a down-turned portion 5 forming a depression or a shoulder, the outer end of which is again turned down as at 6. Beyond the point 6 said member is bent again at right angles as at 7, and the free end of the member is given an upwardly concave form, thus 25 forming a semicylinder 8. The extreme end of said semicylindrical portion 8 is thickened as at 9.

The upper member 2 is provided with a central aperture 10 adapted to register with the aperture through the projection 3 and with flat portions 11 on either side thereof. At equidistantly spaced points from said aperture 10, the member 2 is bent upwardly as at 12 and then laterally and downwardly 30 to form rebent portions comprising an inner side wall 13, an upper wall 14, and an outer side wall 15. The outer side wall is continued downwardly beyond the plane of the flat portions 11 and is bent laterally and then upwardly to form a second upwardly con-

cave rebent portion comprising an inner side wall 15, an end wall 16, and an outer side wall 17. The ends of the member 2 are then again bent laterally as at 18 and formed as downwardly concave semicylinders 19 having their ends thickened as at 20. It will be seen that the portion 11 of the member 2 lies upon the flat portion of the member 1 while the walls 15 of the downwardly concave rebent portions of the member 2 overlie the inner walls of the depressions or shoulders 5 of the member 1, the end walls 16 of the upwardly concave rebent portions of the member 2 rest upon said shoulders 5, and the semicylindrical portions 19 of the member 2 register with the semicylindrical portions 8 of the member 1 to form cylindrical sockets.

35 The side walls 13 and 15 of the downwardly concave rebent portions of the member 2 are tapped as at 21 and 22 for the reception of set screws 23 adapted to position the dies (not shown) which are received in the stock. It will be noted that the upper member 2 is provided with upwardly projecting rebent portions 24, 25, 26, and 27, comprising side walls 28 and 29 pressed closely together to form guide ways for said dies. Flanges 30 extend laterally from said rebent portions forming said guide ways. It will be noted that each of the rebent portions 24, 25, 26, and 27 is provided with a curved end 31 to permit the insertion in the guideways of dies (not shown). After the members 1 and 2 have been formed as above described, they are suitably secured together as by 40 welding, and apertures 32 are tapped through the two members in such position as to be included in said nubs 4 of the member 1. These apertures 32 are for the reception of clamping bolts (not shown) adapted to secure the dies in adjusted position. The internal surfaces of the cylindrical sockets formed by the portions 8 and 19 of the members 1 and 2 are screw-threaded as at 33 for the reception of handle members whereby the stock 45 may be rotated.

45 Other modes of applying the principle of my invention may be employed instead of the one explained, change being made as regards the mechanism herein disclosed, provided the 50

means stated by any of the following claims or the equivalent of such stated means be employed.

I therefore particularly point out and distinctly claim as my invention:

- 5 1. A die-stock comprising a plate formed with a plane portion having a central aperture therethrough, and a depressed flange at each end of said portion, a second plate secured to said first plate and formed with an aperture registering with said first-mentioned aperture, means on said second plate forming guideways, stop means on said second plate at the outer end of each of said guideways, and means on said second plate co-operating with each of the flanges on said first plate for effecting rigid assembly of said plates.
- 10 2. A die-stock comprising a plate formed with a plane portion having a central aperture therethrough, and a depressed flange at each end of said portion, a second plate secured to said first plate and formed with an aperture registering with said first-mentioned aperture, a pair of upstanding flanges on said second plate extending from said aperture toward each end of said plate, stop means adjacent the outer end of each of said pairs of flanges, and means on said second plate cooperating with each of the flanges on said first plate for effecting rigid assembly of said plates.
- 15 3. A die-stock comprising a plate formed with a central aperture therethrough, and a depressed flange adjacent each end thereof, a second plate secured to said first plate and formed with an aperture registering with said first-mentioned aperture, a pair of integral upstanding flanges on said second plate extending from said aperture toward each end of said plate, integral stop means adjacent the outer end of each of said pairs of flanges, and means on said second plate cooperating with each of the flanges on said first plate for effecting rigid assembly of said plates.
- 20 4. A die-stock comprising a plate formed with a plane portion having a central aperture therethrough, and a depressed flange at each end of said portion, a second plate secured to said plane portion and formed with an aperture registering with said first-mentioned aperture, a pair of upstanding flanges on said second plate extending from said aperture toward each end of said plate, an upstanding lug on said second plate adjacent the outer end of each of said pairs of flanges, and a set-screw threaded through each of said lugs and forming an adjustable stop.
- 25 5. A die-stock comprising a plate formed with a central aperture therethrough, and a depressed flange adjacent each end thereof, a second plate secured to said first plate and formed with an aperture registering with said first-mentioned aperture, a pair of upstanding flanges on said second plate extending from said aperture toward each end of said plate, an upstanding lug on said second plate adjacent the outer end of each of said pairs of flanges, and a set-screw threaded through each of said lugs and forming an adjustable stop.

standing flanges on said second plate extending from said aperture toward each end of said plate, an upstanding lug on said second plate adjacent the outer end of each of said pairs of flanges, a set-screw threaded through each of said lugs and forming an adjustable stop, and means on said second plate cooperating with each of the flanges on said first plate for effecting rigid assembly of said plates.

Signed by me this 15th day of February, 1928.

RALPH E. HYDE.
